UNITED STATES PATENT OFFICE.

SAMUEL GRAHAM, OF LEBECK, MISSOURI.

VEHICLE-STANDARD.

SPECIFICATION forming part of Letters Patent No. 425,070, dated April 8, 1890.

Application filed February 18, 1890. Serial No. 340,863. (No model.)

To all whom it may concern:

Be it known that I, SAMUEL GRAHAM, a citizen of the United States of America, residing at Lebeck, in the county of Cedar and State 5 of Missouri, have invented certain new and useful Improvements in Vehicle-Standard Keys, of which the following is a specification, reference being had therein to the accompanying drawings.

10 My invention relates to an adjustable key for securing a vehicle-standard to the bolster, and particularly that class of standards shown and described in my former patent, No. 416,910.

15 My object is to produce means whereby a vehicle-standard can be adjustably and at the same time securely fixed on the bolster end.

With this end in view my invention 20 consists in certain peculiarities of construction and combinations of parts more fully described hereinafter, and pointed out in the claims.

25 Referring to the accompanying drawings, Figure 1 represents a side elevation of my complete arrangement of parts; Fig. 2, a bottom view, and Fig. 3 a detail view, of the key.

The reference-letter B indicates the bolster end, and A the standard, preferably of the 30 form shown in my prior patent before mentioned, having an encircling-band C arranged to loosely surround the said bolster. The bolster is provided with the usual beveled lower surface *a*, and between this surface and the band C is inserted the key D. This key 35 consists of a metallic plate, wedge-shaped in longitudinal section or elevation and having a width equal to that of the inside of the band C.

The inner end of the key is bifurcated to form a pair of arms *c* and a longitudinal open slot 40 *e* between them, and projecting spurs or lugs *d* are formed on the inner ends of said arms. The arms *c* are also serrated or provided with teeth *f* on their under surfaces, as seen more clearly in Fig. 3.

45 Through the bolster behind the standard extends a vertical bolt E, which also engages the slot *c*, and is provided on its lower end with a nut *g* and washer *h* between the latter and the plain surface of the plate D.

The preferred construction of my device 50 having been set forth, I will now proceed to describe the mode of application of the same. The key is first placed in the band C to rest upon the lower wall of the same, with the spurs *d* projecting from its inside edge. The 55 standard is now placed on the bolster and set at the desired adjustment or distance from the outer extremity of said bolster. The key will next be driven home until it is tightly wedged between the band C and the bolster, the arms 60 *c* passing on either side of the bolt E, which has been previously driven through the bolster. The nut *g* is then screwed up as tight as possible on the bolt, and the teeth *f* in the upper surface of the arms *c*, will be forced 65 into the wood of the bolster, and the key thus rigidly clamped to the latter. When the standard has been thus secured, it will be seen that it will maintain a perpendicular position 70 in relation to the bolster as the taper of the surfaces of the wedge or key *c* corresponds to that of the under side *a* of the bolster, and thus the lower face of the key and the upper surface of said bolster will be parallel and hold the standard at right angles to them. 75

It will be readily seen that the standard can be adjusted to any position on the bolster between the end of the latter and the bolt *g* and locked at any point, and also that the lugs *d* will prevent the removal of the key without the standard. It can be easily adjusted 80 to suit a narrow or wide tread vehicle, and also fitted to a key or other frame. It can be removed entirely, if desired, and can also be changed to suit the swelling or shrinkage of 85 the wagon-bed.

It is evident that my device might be varied in many slight ways which might suggest themselves to a mechanical mind, and hence I do not limit myself to the exact construction 90 herein shown.

Having thus described my invention, what I claim as new, and desire to secure by Letters Patent, is—

1. The combination of the bolster, the standard, and a wedge inserted between them, substantially as and for the purpose described. 95
2. A key arranged to be inserted between

the standard and bolster, and consisting of a wedge-shaped plate provided with an adjustment-slot, substantially as described.

3. The combination of the bolster, the standard provided with a band encircling the latter, a key inserted between said band and said bolster and provided with a slot, and a bolt extending through said bolster and said slot, substantially as described.

10 4. A key inserted between the standard and

bolster, and consisting of a wedge-shaped plate having a roughened face, substantially as and for the purpose described.

In testimony whereof I affix my signature in presence of two witnesses.

SAMUEL GRAHAM.
